(57) CLAIM

The ornamental design for a pair of shoes, as shown and described.

DESCRIPTION

FIG. 1 is an anterior (front) view of one of the pair of shoes;

FIG. 2 is a posterior (rear) view of the shoe of FIG. 1;

FIG. 3 is a medial view of the shoe of FIG. 1;

FIG. 4 is a lateral view of the shoe of FIG. 1;

FIG. 5 is a top view of the shoe of FIG. 1; and,

FIG. 6 is a bottom view of the shoe of FIG. 1.

The shoe shown in FIGS. 1-6 is for a left foot. The shoe for a right foot is a mirror image of the shoe for a left foot.

The dashed broken lines are for environmental purposes only and form no part of the claimed design.
